CLAIM

The ornamental design for a packaging unit of caps for
marking pins, as shown and described.

DESCRIPTION

FIG. 1 is a bottom perspective view of a packaging unit
for caps for marking pins showing my new design;
FIG. 2 is a top plan view thereof;
FIG. 3 is a side elevational view thereof;
FIG. 4 is an end elevational view taken from the left of
FIG. 2;
FIG. 5 is an end elevational view taken from the right of
FIG. 2;
FIG. 6 is a bottom plan view thereof; and,
FIG. 7 is the bottom perspective view of FIG. 1 with
marking pins inserted in the caps, the marking pins not
forming a part of this invention and being shown in
dotted lines.
